UNITED STATES PATENT OFFICE.

PERCY WALTER BANKS AND ALFRED NORRIS BURT, OF WELLINGTON, NEW ZEALAND, ASSIGNORS TO DETACHABLE HEELS LIMITED, OF WELLINGTON, NEW ZEALAND, A COMPANY OF NEW ZEALAND.

HEEL OF FOOTWEAR.

Application filed October 10, 1924. Serial No. 742,917.

To all whom it may concern:

Be it known that PERCY WALTER BANKS and ALFRED NORRIS BURT, citizens of the Dominion of New Zealand, residing at Wellington, New Zealand, have invented certain new and useful Improvements in Heels of Footwear, of which the following is a specification.

This invention relates to heels of foot-
wear of the class wherein the heels are
formed in two portions, detachably secured
together by interengaging members on the
said portions. For convenience of descrip-
tion the two said portions are hereinafter
referred to as a "heel portion" and a "de-
tachable portion" respectively.

The object of the invention is to provide
improved means for securing the two said
portions of the heel together in order that
the heels may be produced more economical-
ly than heretofore and without detracting
from their appearance.

According to the invention, the securing
means consists of separate parts formed
from a single plate, the area of which does
not substantially exceed the area of the
heel on which the securing means are used.

One part of the securing means consists
of a triangular plate affixed to the heel portion
with its apex rearward and its base at
the front of the converging sides having
their edges bent so that they are set out
from the latter to form a locking or securing
flange for the other part which con-
sists of a plate affixed to the detachable portion
and having a V shaped opening with
the apex part likewise rearward.

In securing the two portions together the
edges of the V shaped opening on the de-
tachable portion engage the edges of the tri-
angular plate on the heel portion, suitable
means being provided for locking the de-
tachable portion in place.

In the accompanying drawings in con-
junction with which the invention will be
further described:—

Figure 1 is a part side view of a shoe
having a heel constructed and fitted ac-
cording to the invention.

Figure 2 is a view of the heel portions
showing a triangular plate secured thereto.

Figure 3 is a view of the detachable por-

tion showing a plate having a V shaped
opening secured thereto.

Figure 4 is a vertical cross sectional view 55
of the heel with the two portions locked
together.

The heel comprises a heel portion 1 per-
manently attached to the shoe 2, and a de-
tachable portion 3. 60

The portion 1 has affixed to its under side
a triangular shaped plate 4, the base 4^a of
which is located right at the front of the
heel portion 1 and conforms to the shape
thereof, while the other sides of said plate 65
4 converge towards the rear of said heel
portion 1. The converging edges 5 of the
plate 4 are bent or set out or away from
the under side of the heel portion 1 as
shown in Figure 4. 70

The detachable portion 3 has affixed to
its upper side a plate 6, having a V shaped
opening 6^a which extends right from the
front of the portion 3 and tapers towards
the back thereof the same distance and de- 75
gree as the plate 4 of the heel portion 1.

The heel portion 3 contains grooves 3^a
opposite the inner edges of the plate 6 to
accommodate the outward set edges 5 of the
plate 4 when the plate 6 is slid on to the 80
latter from the back of the heel so as to be-
come engaged therewith as shown in Fig-
ure 2.

The plate 6 is provided with projections
8 at its front end, said projections, after 85
the plate 6 has been slid into engagement
with the plate 4, being turned upwards to
engage the heel portion 1, and so prevent
the detachable portion 3 from becoming de-
tached unless required. 90

If desired, the plate 4 can be secured to the
detachable heel portion 3, and the plate 6
to the fixed heel portion 1 in which case
the detachable heel portion would be slid
onto the fixed heel portion from the front 95
of the heel, and the projections would be
turned downwards to prevent the detachable
portion from coming off the fixed portion.

Instead of a plate 6, strips of metal can
be secured to the heel portion, said strips 100
being arranged to provide a V shaped open-
ing similar to that shown.

In forming the means for securing the
two heel portions together the plate 4 and

plate 6 are obtained from a single plate the area of which is only slightly the larger (to the extent of the projections 8) than the area of the heel to which the device is to be fitted.

The portion removed when making the V shaped opening in the plate 6 is utilized as the triangular plate 4 the said cut out part having its apex cut off to enable it to be moved further into the V shaped opening, so that when provided or formed with outwardly set edges as at 5, the latter will engage behind the edges of the V shaped opening.

15 With a heel in two portions, fitted together by the means described, only one thickness of metal is visible, or if strips be used instead of the plate 6, no metal need be visible.

20 What we do claim and desire to obtain by Letters Patent of the United States of America is:—

1. A heel for footwear, comprising, a fixed and a detachable heel portion, a plate having a V shaped opening secured to one portion, a V shaped plate with offset edges fixed to the other portion, the edges forming a locking flange for the edges of the V shaped opening of the first said plate, the V shaped portions of each plate extending to the inner edges of the respective heel portion.

25 2. A heel for footwear, comprising, a fixed and a detachable heel portion a plate having a V shaped opening secured to one portion, a V shaped plate with offset edges fixed to the other portion, the edges forming a locking flange for the edges of the V shaped

opening of the first said plate, the V shaped portions of each plate extending to the inner edges of the respective heel portion, said 40 V shaped plate being secured to the fixed heel portion with its base at the front thereof, and said other plate being secured to the detachable portion, the plate with the V shaped opening having projections extending beyond the heel to be bent over the fixed heel portion to secure the two portions together.

3. A heel for footwear, comprising, a fixed and a detachable heel portion, a plate having a V shaped opening secured to one portion, a V shaped plate with offset edges fixed to the other portion, the edges forming a locking flange for the edges of the V shaped opening of the first said plate, the V shaped portions of each plate extending to the inner edges of the respective heel portion, said 50 V shaped plate being secured to the fixed heel portion with its base at the front thereof, and said other plate being secured to the detachable portion, the plate with the V shaped opening having projections extending beyond the heel to be bent over the fixed heel portion to secure the two portions together, wherein the two said plates are cut 55 from a single plate the area of which exceeds the area of the heel on which the plates are to be used only to the extent required by said projections.

In testimony whereof we have signed our 70 names to this specification.

PERCY WALTER BANKS.
ALFRED NORRIS BURT.
